UNITED STATES PATENT OFFICE.

GALEN A. GOSS, OF DURAND, WISCONSIN.

HIGHWAY-MAINTENANCE ATTACHMENT FOR MOTOR-TRUCKS.

1,304,557.

Specification of Letters Patent. Patented May 27, 1919.

Application filed May 13, 1918. Serial No. 234,239.

To all whom it may concern:

Be it known that I, GALEN A. Goss, a citizen of the United States, and a resident of Durand, in the county of Pepin and State 5 of Wisconsin, have invented certain new and useful Improvements in Highway-Maintenance Attachments for Motor-Trucks, of which the following is a specification.

This invention relates to an attachment 0 for motor trucks which is particularly designed for highway maintenance work and the primary object of the invention is to provide an attachment for an ordinary motor truck, of any desired type or size, which may 5 be used in lieu of the usual type of drag, planer or scraper used for properly surfacing highways or roads, eliminating the inconveniences contingent with dragging surface planers, scrapers or the like behind a 10 truck, and providing a device by means of which a much greater highway surface may be prepared, than is possible to prepare with an ordinary surfacing device drawn by 15 horses, in the same period of time.

More specifically, this invention comprehends the provision of a pair of standards 20 which are supported above the floor or platform of an ordinary motor truck and pivotally supports levers to which are connected 25 supporting hanger structures, to detachably connect the desired type of surfacing tool to the lower end of these hangers, and to further provide an auxiliary hand lever which is carried by each of the vertically adjusting 30 tool levers, for varying the angle with respect to the horizontal, of the surfacing 35 tools.

Other objects of the invention will appear 40 in the following detailed description, taken 45 in connection with the accompanying drawings, forming a part of this specification, and in which drawings:

Figure 1 is a side elevation of the truck 50 having the highway maintenance attachment 55 applied thereto, and having one of the rear wheels of the truck removed.

Fig. 2 is a rear elevation of the truck 60 showing the invention applied thereto, and having parts of the truck broken away.

Fig. 3 is a perspective view of a cutting or 65 surfacing blade to be used in connection with the attachment, and

Fig. 4 is a fragmentary perspective view 70 of one of the hanger structures of the device.

Referring more particularly to the drawings, A designates a motor truck of any ordinary

nary construction having a rear platform B, and suitable supporting girders C.

The road or highway surfacing attachment is carried by the platform B of the 60 truck A, and it includes a pair of blades 1 and 2 which are provided for working the surface of a road or highway.

The blade 1 is carried by the lower ends of a pair of vertical bars 3 and 4, which in connection with the head or cross bar structure 5 and the vertical bar 6 forms the suspending hanger for the blade 1. The cross bar or head structure 5 comprises spaced bars 7 and 8 which are attached one upon each side 70 of the upper ends of the vertical bars 3 and 4, and between and to which the vertical bar 6 is pivotally connected by means of a bolt 9. Suitable angled braces 10 extend diagonally across the upper corners of the 75 suspending or supporting hanger structure. The vertical bar 6 has its upper end connected to one end of a hand lever 12 which is pivotally supported intermediate its ends by a standard structure 13. The standard 80 structure 13 includes a pair of spaced bars 14 and 15 the lower ends of which angle outwardly to form bracing legs as shown at 16, and an upper and lower vertical bar 17 and 18 between the facing ends of which the 85 lever 12 extends, as clearly shown in the drawings. The lower bar 18 has its lower end forked and angled to form bracing legs 19. The lower ends of the bracing legs 16 and 19 are angled to form feet which engage 90 against and are attached to the platform B.

A quadrant 20 is attached to the bars 17 and 18 and it is adapted for co-action with a dog mechanism 21 carried by the lever 12 for holding the lever 12 in adjusted position, 95 for holding the blade 1 at various adjusted elevations.

The hand lever 12 has a relatively short hand lever 22 pivotally connected near the handle end thereof as shown at 23 and this 100 hand lever carries a dog mechanism 24 which co-acts with a quadrant 25 carried by the hand lever 12. A cable 26 is connected to the hand lever 22 and passes over a grooved pulley 27 which is carried by the hand lever 105 12. The cable 26 has its lower end connected to the head structure 5 of the suspending hanger structure, to one side of the pivotal support 9 of the hanger structure so that by the adjustment of the position of the 110 hand lever 21, the angle of the blade 1 with respect to the horizontal may be varied as

desired for regulating the shedding incline of the road surface.

Suitable supporting rods 28 and 29 are connected to the blade 1 and they are connected, by means of hooks 30 formed upon their upper ends to suitable eyes 31 carried by the truck structure. The rods 28 and 29 brace the blade 1 during the operation of the road surfacing device, and their connection, 10 with the truck permits of unimpeded adjusting movement of the blade. The rod 28 is bowed intermediate its ends as shown at 30', to allow sufficient movement of the rod 28 which is connected to the blade 2.

15 A stay chain 31' is attached to the blade 1, by a suitable attaching bar 32 and to the under surface of the truck, as shown at 33.

The blade 1 has a smoother plate 34 attached to the forward face thereof at its 20 lower edge and if it is so desired, an ordinary cutting blade may be attached in lieu of the smoother, or the particular type of cutter blade, as indicated at 35, in Fig. 3 of the drawings. This cutting blade 35 has a 25 relatively straight portion 36 and a forwardly curved sharpened lower edge 37. The straight portion is provided with bolt receiving openings 38 to attach it to the blade 1. The blade 1 has a shield 39 attached 30 to the forward surface of the same along a portion of the upper edge, extending along the upper edge of the blade from the forward end thereof, to prevent the dirt from passing over the upper edge of the blade.

35 The structure connected to the blade 2, for operating the blade, etc., is identical with the structure relating to and co-acting with the blade 1.

The blades 1 and 2 are disposed at oblique 40 angles to each other and to the line of travel of the trucks, as is ordinary in disposing the surface working blades of road scrapers, or surfacing tools, and to obtain the most efficient results.

45 The blades 1 and 2, are, as will be noted from the foregoing description and drawings, mounted for adjustment independently of each other, so that if it is desired, one of the blades and the tools carried thereby may 50 be raised upwardly out of a ground engaging position, while the upper blade is in a ground engaging or highway surfacing position thereby permitting one of the blades to be used independently of or in conjunction with 55 the other as desired. The hand lever 22, and cable 26 connected thereto, permit of pivotal adjustment of the carrying frame, and consequently the blades 1 and 2, to adjust the angles of these blades with respect to the 60 horizontal, either one, independently of the other.

Having thus fully described the invention, what is claimed is:

1. In a highway maintenance attachment 65 for motor trucks, a surface working blade,

a supporting structure attached to said blade, a pivoted hand lever, a bar connected to said hand lever and pivoted to said supporting structure for adjusting the elevation of said blade upon pivotal movement of 70 said hand lever, an auxiliary hand lever pivotally carried by said first named hand lever, and a cable connected to said auxiliary hand lever and said supporting structure for tilting the supporting structure and blade upon 75 its pivotal support upon pivotal movement of the auxiliary hand lever.

2. The combination with a motor truck, of a highway maintenance attachment therefor comprising a surface working blade, a 80 supporting hanger attached to said blade, a pivotally supported hand lever, a bar connected to said hand lever and pivotally connected to said supporting hanger for adjusting the elevation of said blade upon movement of the hand lever, an auxiliary hand lever pivotally carried by said first named hand lever, a cable connected to said auxiliary hand lever and to said supporting hanger, whereby said supporting hanger will 90 be moved upon its pivot upon pivotal movement of the hand lever to vary the longitudinal angle of the blade with respect to the horizontal, bracing rods attached to said 95 blade and connected to the body of said truck to permit the unimpeded adjusting movement of the blade, and an arcuate sheet metal shield attached to the upper forward surface of said blade.

3. The combination with a motor truck, 100 of a highway maintenance attachment therefor comprising a pair of surface working blades disposed at oblique angles to each other and to the line of travel of the truck, standards carried by said truck, hand 105 levers pivotally connected to said standards, bars connected to the forward end of said hand levers, supporting hangers for said blades pivotally connected to the lower ends of said bars whereby the said blades will be 110 adjusted vertically upon pivotal movement of said levers, auxiliary hand levers pivotally carried by said first named levers, cables connected to said auxiliary hand levers and to said supporting hangers for moving the 115 supporting hangers and blades upon their pivotal supports to vary the longitudinal angle of said blades with respect to the horizontal.

4. The combination with a motor truck, 120 of a highway maintenance attachment therefor comprising a pair of surface working blades disposed at oblique angles to each other and to the line of travel of the truck, standards carried by said truck, hand levers 125 pivotally connected to said standards, bars connected to the forward end of said hand levers, supporting hangers for said blades pivotally connected to the lower ends of said bars whereby the said blades will be ad- 130

justed vertically upon pivotal movement of said levers, auxiliary hand levers pivotally carried by said first named levers, cables connected to said auxiliary hand levers and 5 to said supporting hangers for moving the supporting hangers and blades upon their pivotal supports to vary the longitudinal angle of said blades with respect to the horizontal, and stay members attached to said 10 blades and said motor truck.

5. In a highway maintenance attachment for motor trucks, a surface working blade, a supporting structure attached to said blade, a pivoted hand lever, a bar connected 15 to said hand lever and pivoted to said supporting structure for adjusting the elevation of said blade upon pivotal movement of said hand lever, an auxiliary hand lever pivotally carried by said first named hand lever, a 20 cable connected to said auxiliary hand lever

and said supporting structure for tilting the supporting structure and blade upon pivotal movement of the auxiliary hand lever, and means connecting said blade to said truck to maintain the blade at a predetermined oblique angle to the line of travel of the truck. 25

6. The combination with a motor truck, of a highway maintenance attachment therefor comprising a surface working blade, means connecting said blade to said truck to 30 maintain the blade at a predetermined angle to the line of travel of the truck, means for adjusting the elevation of said blade, and means for adjusting the longitudinal angle of the blade with respect to the horizontal, 35 including a lever carried by said elevation adjusting means, a cable, and cable guiding means carried by said elevation adjusting means.

GALEN A. GOSS.
